UNITED STATES PATENT OFFICE

122,821

DESIGN FOR A CARPET OR SIMILAR ARTICLE

Frank A. Haas, New York, N. Y.

Application August 7, 1940, Serial No. 94,274

Term of patent 7 years

To all whom it may concern:

Be it known that I, Frank A. Haas, a citizen of the United States of America, residing in New York city, county of New York and State of New York, have invented a new, original, and ornamental Design for a Carpet or Similar Article, of which the following is a specification, reference being had to the accompanying drawing, forming part thereof, wherein,

The figure is a plan view of a piece of carpet showing my new design.

I claim:

The ornamental design for a carpet or similar article, as shown.

FRANK A. HAAS.
